UNITED STATES PATENT OFFICE

ROBERT C. PIERCE, OF NILES, MICHIGAN, ASSIGNOR TO NATIONAL STANDARD COMPANY, OF NILES, MICHIGAN, A CORPORATION OF MICHIGAN

DESIGN FOR A FLOOR LAMP

Application filed October 19, 1932. Serial No. 45,416. Term of patent 14 years.

To all whom it may concern:

Be it known that I, ROBERT C. PIERCE, a citizen of the United States, residing at Niles, in the county of Berrien and State of Michigan, have invented a new, original, and ornamental Design for a Floor Lamp, of which the following is a specification, reference being had to the accompanying drawing, forming a part thereof, in which:

The figure of the drawing is a view in side elevation.

The basket work ornamentation shown in full lines on the shades is repeated over the body of said shades, and the crisscross ornamentation shown in full lines on the lower portion of the support rod, is repeated over the body of said lower portion of the support rod.

I claim:

The ornamental design for a floor lamp as shown and described.

ROBERT C. PIERCE.
